UNITED STATES PATENT OFFICE.

EDWARD C. POAGE, OF CINCINNATI, OHIO.

CHATELAINE-HOOK.

SPECIFICATION forming part of Letters Patent No. 689,905, dated December 31, 1901.

Application filed November 20, 1901. Serial No. 83,018. (No model.)

To all whom it may concern:

Be it known that I, EDWARD C. POAGE, a citizen of the United States, residing in the city of Cincinnati, in the county of Hamilton and State of Ohio, have invented certain new and useful Improvements in Chatelaine-Hooks; and I do declare the following to be a full, clear, and exact description thereof, attention being called to the accompanying drawings, with the reference letters and numerals marked thereon, which form also a part of this specification.

This invention relates to improvements in chatelaine-hooks, being a fitting whereby a so-called "chatelaine-bag" forming part of a lady's toilet outfit is suspended from the belt.

The improvement relates more specifically to means for locking such a hook in position after placed over the belt, the particular feature of these locking means being a construction simplifying their operation and whereby the attached bag serves as an assisting factor, partly by positive action and partly automatically and by its weight merely.

In the following specification, and particularly pointed out in the claims following, is found a full description of the invention, together with its manipulation, parts, and construction, which latter is also illustrated in the accompanying drawings, in which—

Figure 1 is a front view of the device as used in connection with a chatelaine-bag for supporting the same on a belt and locking it thereto. Fig. 2 is a similar view with the bag omitted, the locking means being shown in inoperative position. Fig. 3 is a rear view of the detached hook as shown in the preceding figure and with parts broken away. Figs. 4 and 5 are side views of the same, the first showing the locking means in operative position, as is shown in Fig. 1, the other unlocked, as shown in Fig. 2, to admit detachment of the hook from the belt. Fig. 6 is a perspective view of certain parts of the device shown disconnected.

In the drawings, A is the hook, consisting of two members bent over and doubled up on each other as shown, the inner member 10, when the hook is placed in position, passing down behind the belt 11, the outer member 12 passing down in front of the belt. The end of one of these members, preferably the

outer one, is so shaped as to form an eye 13 at its lower end, which receives a link 14, to which the chatelaine-bag 15 is attached by any suitable means, usually by two straps 16. The front side of the hook—that is, of member 12—may be covered with a material corresponding in appearance to the material of the bag, or it may bear an ornamental face-plate soldered or riveted thereto, as shown in dotted outlines in Fig. 1. For holding this hook positively in position on the belt I provide a clamp of the opposing members, of which one is formed by one of the members 65 of the hook, the rear one in this case, while the other member 17 is hingedly connected to the inner side of the other member of the hook. The opposite surfaces of these clamping members are preferably provided with 70 serrations 18 to secure a firmer attachment to the belt. The necessary lugs and bearings to secure this pivotal attachment are preferably formed integrally with the other parts, which may be readily done, since they 75 are all intended to be of sheet metal. For such purpose bearings 19 are struck up from member 12, the metal necessary for them being received by being cut out of the main body. Complementary bearings 21 are formed on 80 clamping member 17, between the ends thereof, by bending portions of the metal on the edges accordingly. The attachment is completed by passing a pivot-pin 22 through all these bearings.

The clamping-jaws are kept normally apart, as shown in Fig. 5, by a spring suitably placed—as, for instance, by a coil-spring 23, which is supported on pin 22, and the ends of which, tending to move in opposite directions, 90 bear one against the pivotally-supported clamping member and the other against member 12 of the hook. For closing the clamp against the belt, as shown in Fig. 4, the lower end of the movable clamping member 17 is 95 moved toward member 12 by link 14 and held so by the same. For such purpose eye 13, within which link 14 is confined, is elongated and also gradually enlarged rearwardly and upwardly to permit said link to be moved accordingly. Thus, for instance, in the normal position shown in Fig. 5 the link would be in the upper part of eye 13 and also in the rearwardly-enlarged part thereof, where its posi-

tion is such as to be without effect upon the position of jaw 17. On being moved down, however, in the narrowest part of eye 13, as shown in Fig. 4, it will bear against the lower part of the clamping-jaw and by swinging the same in one direction will cause the upper part thereof to move in the other direction and approach the opposite clamping member. It will thus be seen that it is only necessary to give a slight tug on the bag and the hook is locked in position on the belt, and when the weight of the bag is sufficient such locking will occur automatically, since the weight of the bag will pull the ring down. In all cases, however, this weight favors the retention of the parts in their locking position. It may be further favored by a slight contraction or dent in the metal, as shown at *a*, which ordinarily prevents the link from moving up freely, but which readily yields when the link is positively moved up for disengaging the clamp.

Eye 13 is preferably constructed as shown, consisting of a part of member 12, being a part in excess of the length, which part is turned up and over, as shown, and at its upper end connected again to the main body, where it is permanently attached. This attachment may be by solder, rivets, or, as shown, a part of the metal—that is, the extreme end *b* of the turned-up part being passed through an opening *c* and turned down. This part of the metal of member 12 which forms this eye 13 is narrower than the main part, and the lower part of the swinging member 17 is correspondingly cut out, as shown at *f*, to clear in its movements eye 13.

It is clear that this hook as so improved with this locking device is not necessarily limited in its use to chatelaine-bags only, but may be used in connection with other articles for the purpose of suspension or connection.

Having described my invention, I claim as new—

45 1. In a supporting-hook, the combination with the two members thereof, of a clamping member supported between them and pivotally connected to one of the members of the hook and forming in conjunction with the other member a clamping device, a link serving as a means to attach the article to be supported, an eye on the hook which this link occupies and within which it may be moved up or down, and a spring to keep the members of the clamping device normally apart, said function also causing part of the pivotally-supported clamping member to project into the path of the link within the eye it occupies, so that a change of position of the link from one 55 part of the eye to the other involves also an operation of the clamping device.

2. In a supporting-hook, the combination with the two members thereof, of a clamping member supported between them and pivotally connected to one of the members of the hook and forming in conjunction with the other member a clamping device, an eye formed at the lower end of the hook member first mentioned, the clear opening of said eye being wider at its upper part and decreasing downwardly, a link serving as a means to attach the article to be supported occupying this eye and within which it may be moved up or down and from the wider into the narrower part of the opening thereof and a spring to keep the two members of the clamping device normally apart, causing at the same time part of the pivotally-supported clamping member to project into the way of the link in a manner to prevent movement of the same from the wider part of the opening of the eye into the narrower one without operating the clamping device at the same time.

3. In a supporting-hook, the combination with the two members 10 and 12 thereof, of a clamping member 17 pivotally attached to the inner side of member 12 so as to be able to form with member 10 a clamping device, an eye 13 formed on the lower end of member 12, a link 14 occupying this eye and capable to be moved up or down therein and a spring to hold the two clamping members normally apart causing at the same time parts of member 17 to project over eye 13 in a manner to lie in the path of link 14.

4. A supporting-hook having members 10 and 12, the latter having inwardly-projecting lugs 19 forming bearings and having its lower end turned rearwardly and upwardly to form an eye 13 thereat, a link 14 in this eye free to be moved up or down therein, a clamping member 17 having similar bearings 21 between its ends, a pivot-pin adapted to be passed through all these bearings whereby member 17 becomes attached to member 12 in a manner to be free to swing to or from member 10 with which it forms a clamping device, its lower end being cut out to clear the lower part of member 12 which forms eye 13, the remaining parts of member 17 projecting down on each side of this eye and a spring to normally hold the upper or clamping end of member 17 away from member 10 causing its lower end to project over the clear opening of eye 13 and in the path of link 14 as the same is moved from one part of eye 13 to the other.

In testimony whereof I hereunto set my hand in the presence of two witnesses:

EDWARD C. POAGE.
